(57) **CLAIM**

The ornamental design for room control unit, as shown and described.

DESCRIPTION

FIG. 1 is a front elevation view of the room control unit
FIG. 2 is a rear elevation view of the room control unit
FIG. 3 is a top view of the room control unit
FIG. 4 is a bottom view of the room control unit
FIG. 5 is a left-side view of the room control unit
FIG. 6 is a right-side view of the room control unit; and,
FIG. 7 is a front perspective view of a room control unit.
The broken line showing of room control unit is for illustrative purposes only and forms no part of the claimed design.

1 Claim, 7 Drawing Sheets
